UNITED STATES PATENT OFFICE.

FRANCK AGNICHEK, OF CHICAGO, ILLINOIS, ASSIGNOR OF ONE-FOURTH TO FRANK KRASEL, ONE-FOURTH TO JOSEPH BOSCH, AND ONE-FOURTH TO LOUIS I. GOTTLIEB, ALL OF CHICAGO, ILLINOIS.

CAR WHEEL.

Application filed April 4, 1924. Serial No. 704,200.

To all whom it may concern:

Be it known that I, FRANCK AGNICHEK, a citizen of the United States, residing at Chicago, in the county of Cook and State 5 of Illinois, have invented certain new and useful Improvements in Car Wheels, of which the following is a specification.

This invention relates to new and useful improvements in car wheels, principally of 10 the type used on vehicles adapted to travel over rails.

One of the important objects of the present invention is to provide a car wheel of the character described which is of such a 15 construction as to eliminate a great deal of the unnecessary noises now made by the vehicles when the same are traveling over the rails.

A still further object of the invention is 20 to provide an improved car wheel of the above mentioned character, wherein the parts are so arranged as to enable the same to be readily disassembled whenever necessary in order to replace the worn parts.

25 A further object of the invention is to provide a car wheel of the above mentioned character, which is simple in construction, inexpensive, strong and durable and furthermore adapted for the purposes for 30 which it is designated.

Other objects and advantages of this invention will become apparent during a course of the following description.

In the accompanying drawing forming a 35 part of the specification, and in which like numerals designate like parts throughout the same,

Figure 1 is a side elevation of my improved car wheel,

40 Figure 2 is a vertical section taken therethrough, and

Figure 3 is a sectional view taken approximately on line 3-3 of Figure 2.

In the drawing wherein for the purpose 45 of illustration is shown the preferred embodiment of my invention, the numeral 1 designates the body portion of my car wheel and the same is cast of any suitable metallic material in the manner well known in the art. Extending circumferentially around the peripheral face of the body portion is the rib or flange 2. The portion of the peripheral face of the body portion 1 between the rib 2 and the rear face of the wheel

provides a brake drum 3 for the purposes 55 also well known in the art.

The body portion 1 is further provided on the opposite side of the rib 2 with the annular groove 4 which is also formed in the peripheral face of the body portion and 60 the front face 5 of the body portion of the wheel is cut away to provide a flange 6 for the purpose hereinafter to be more fully described. The diameter of the front face 5 is less than the diameter of the body portion 1 of the wheel as is clearly illustrated in Figure 2 of the drawing. Adapted to be 65 securely supported in the annular groove 4 is the packing ring 7 which is formed of any suitable flexible material, preferably 70 rubber, although it is to be understood that any other suitable material may be substituted therefor, and I do not wish to limit myself to the particular kind of material which is to be used. When the rubber ring 75 7 is in position in the groove 4, the tread portion 8 of the wheel is adapted to extend therearound and the tread portion is also in the form of a ring and is provided with the annular flange 9 which extends inwardly 80 therefrom and cooperates with the flange 6 formed on the front face 5 for retaining the rubber ring 7 in position within the groove 4. As is further shown in Figure 2 of the drawing, the annular flange 9 is slightly 85 spaced from the flange 6 and this space 10 provides a means for permitting the inward movement of the tread portion 8 in such a manner as to prevent the possibility of the flange 9 on the tread portion from coming 90 in contact with the flange 6 on the front face 5 so as to cause any unnecessary noises.

The rear face of the tread portion 8 is provided with the usual bead 11 which is adapted to travel in the groove provided in 95 the rail over which the wheel rides or is adapted to abut the edge of a flat rail in the manner well known in the art.

For the purpose of retaining the tread portion 8 in position on the flexible packing ring, I provide the retaining ring 12 which fits flush against the front face of the body portion and the tread portion respectively, and the retaining ring 12 is provided with suitable apertures adapted to register 100 with the threaded apertures 13 provided in the front face 5 of the wheel body and suitable fastening bolts such as shown at 14

are adapted to extend through the openings in the retaining ring and are threaded into the threaded openings 13 in the body portion whereby the ring 12 will be securely clamped in engagement with the front faces of the wheel body and tread portion respectively in the manner clearly shown in the drawing. Any number of these fastening bolts may be provided as is deemed necessary. The body portion 1 is further provided with the usual central opening 15 through which is adapted to extend the axle of the vehicle in the usual manner.

By providing a car wheel of the above mentioned character, the usual noises made by the cast wheels now in use upon conveyances which travel over rails are eliminated and furthermore the parts are so arranged as to enable the same to be readily disassembled in order to replace the worn parts with new ones. Further a car wheel of the above mentioned character, will be strong and durable and may be manufactured at a very low cost.

While I have shown the preferred embodiment of my invention, it is to be understood that various changes in the size, shape and arrangement of parts may be resorted to without departing from the spirit of the invention and the scope of the appended claims.

Having thus described the invention, what I claim is:

1. A car wheel comprising a body portion, an annular rib extending upwardly from the peripheral face of the body portion adjacent the rear face thereof, said body portion having an annular groove formed in the periphery thereof adjacent the front face of the body portion and adjacent the annular rib, a packing ring of flexible material in said groove, a tread portion extending around said packing ring and abutting the annular rib, and means for securing the tread portion on the body portion.

2. A car wheel comprising a body portion, an annular rib formed on the peripheral face thereof adjacent the rear face of the body portion, said body portion having an annular groove formed in the periphery thereof adjacent the front face of the body portion and adjacent the annular rib, the front face of the body portion being cut away around its outer edge to provide an annular flange, a packing ring of flexible material supported in said groove, a tread portion extending around said packing ring and having the front face thereof provided with an annular flange adapted to cooperate with the annular flange on the front face of the body portion, the rear face of the tread portion abutting the annular rib, and means for securing the tread portion on said body portion.

3. A car wheel comprising a body portion, an annular rib formed on the peripheral face thereof adjacent the rear face of the body portion, said body portion having an annular groove formed in the periphery thereof adjacent the front face of the body portion and adjacent the annular rib, the front face of the body portion being cut away around its outer edge to provide an annular flange, a packing ring of flexible material supported in said groove, a tread portion extending around said packing ring and having the front face thereof provided with an annular flange adapted to cooperate with the annular flange on the front face of the body portion, the rear face of the tread portion abutting the annular rib, and means for securing the tread portion on said body portion.

In testimony whereof I affix my signature.

Franck Agnichek.
